UNITED STATES PATENT OFFICE.

IGNACE GRUBER, OF NEW YORK, N. Y.

SUSTAINING DEVICE FOR AERIAL VESSELS.

No. 855,945.

Specification of Letters Patent.

Patented June 4, 1907.

Application filed February 23, 1907. Serial No. 358,935.

To all whom it may concern:

Be it known that I, IGNACE GRUBER, a citizen of the United States, and a resident of the city of New York, borough of the Bronx, in the county and State of New York, have invented a new and useful Improvement in Sustaining Devices for Aerial Vessels, of which the following is a full, clear, and exact description.

10 The purpose of the invention is to provide a pneumatic device capable of operation from within a basket or car of a balloon to direct the balloon in one or the other direction or to prevent a too rapid descent of the balloon in the event of a leakage of gas or should the balloon be prone to drop from other causes.

15 Another purpose of the invention is to provide a device of the character described, adaptable to any type of balloon and which will be in complete control of the aeronaut.

20 The invention consists in the novel construction and combination of the several parts as will be hereinafter fully set forth and pointed out in the claims.

25 Reference to be had to the accompanying drawings forming a part of this specification, in which similar characters of reference indicate corresponding parts in all the figures.

30 Figure 1 is a partly sectional side elevation of a balloon having the improvement applied; Fig. 2 is a partly sectional front elevation of a balloon and a front elevation of the improved device applied to the same; and Fig. 3 is a vertical section through a portion of the steering and sustaining device removed from the balloon.

35 A represents the balloon of an aerial vessel, B the basket which is connected with the balloon or gas bag A by means of the ordinary stays or ropes 10. One of these ropes is adapted to support a bearing member for a portion of the sustaining device at each side of the gas bag A, as is shown in Fig. 2, and in the basket or car B a bellows C is located or a 40 pneumatic of any approved type. The body portions D of the sustaining device are in the nature of plates adapted to fit close to the gas bag A, as is shown in Figs. 1 and 2, and the sustaining cable 10 for the body portions 45 D of the said sustaining device is passed through eyes 11 formed at the back of the plates or other means may be employed for connecting the sustaining or supporting rod to said plates D and at the upper portion of each plate D, a segmental housing 12 is formed and each plate D is further provided

at its lower end upon its outer face with an eye 13, as is shown in Figs. 1 and 2.

50 A wheel 14, peripherally grooved, is mounted upon each of the said plates D, and at the central portion of each wheel 14 a strap 15 is secured, and the strap 15 holds in place a nozzle 16, the nozzles being normally horizontally disposed, as is shown in Fig. 1, or the said nozzles can be directed upward or downward 55 according to the direction in which their supporting wheels are carried.

50 A pin 17 extends from the central portion of each housing 12 and a second pin 18 extends from the lower portion of the front of each plate D in vertical alinement with the upper pin 17 and these pins 17 and 18 limit the movement of the nozzles 16. The cable 10 that supports the plates D extends entirely around the upper portion of the gas 75 bag and is carried down to the basket where it is secured in any suitable or approved manner, but each wheel 14 is turned through the medium of independent ropes or rods 19 passed over the peripherally grooved portions of the wheels and each rod 19 is carried downward to the basket B and is attached to the end portions of a pivot bar 20 operated by a suitable handle 21 or its equivalent, so that a nozzle at either side of the balloon can 80 be independently or simultaneously operated, according to the means employed.

85 Each nozzle 16 is connected with a flexible tube 22 and the flexible tubes from opposite sides of the balloon are carried down and are 90 connected with a transverse pipe 23 having suitable valves 23^a, which pipe 23 is within the basket and is connected with the bellows C or the pneumatic by means of a branch pipe 24, the valves 23^a admitting of closing 95 off the supply of air from the bellows to either of the nozzles 16.

100 In the operation of the device, if it is desired to turn to the right-hand, for example, the left-hand nozzle is brought into requisition, the supply of air being cut off from the right-hand when the air is supplied to the said left-hand nozzles by the occupant in the car operating the bellows C with his foot, for example, and if the balloon is 105 to be directed in reverse direction the other nozzle is brought into action. Should there be an escape of gas or should from any cause the balloon tend to fall too rapidly, the ropes 19 are operated to turn the nozzles downward and 110 both nozzles are then brought into action, the force of the air from the nozzles or the

outside current of air tending to sustain the balloon or at least to prevent it from falling quickly. Should a very rapid descent be required the nozzles 16 are made to face upward.

Having thus described my invention, I claim as new and desire to secure by Letters Patent,—

1. In a sustaining device for aerial vessels, the combination with the gas bag of the vessel, of nozzles pivotally mounted at opposite sides of the gas bag, a pneumatic connected with said nozzles, and means for rotatably adjusting the nozzles.
- 15 2. In a sustaining device for aerial vessels, plates secured to opposite sides of the gas bag, a nozzle pivoted upon each plate, devices for turning the said nozzles and a pneumatic connected with said nozzles.
- 20 3. In a sustaining device for aerial vessels, a gas bag, a basket attached to, plates suspended from the gas bag and located at opposite sides thereof, a wheel pivotally mounted on each plate, a nozzle carried by each wheel, means for rotating the wheels from the basket, and a pneumatic carried by the basket adapted to supply air to the said nozzles.

4. In a sustaining device for aerial vessels, a gas bag, a car or basket suspended therefrom, rotatable members located at opposite sides of the gas bag, a nozzle carried by each member, stops limiting the movement of the nozzles, means for operating the said rotatable objects, and a pneumatic within the car connected with the said nozzles.

35 5. In a sustaining device for aerial vessels, the combination with the gas bag and connected car of the vessel and a bellows located within the said car, of wheels located at opposite sides of the gas bag, means for supporting the said wheels, a nozzle carried by each of the said wheels, a pipe connected with the said bellows, connections between the said pipe and the said nozzles, and valves controlling the supply of air from the bellows to each of the said nozzles, as described.

In testimony whereof I have signed my name to this specification in the presence of two subscribing witnesses.

IGNACE GRUBER.
